RAILWAY SWITCH POINT CONNECTION

Edwin C. Larry, Greece, N. Y., assignor to General Railway Signal Company, Rochester, N. Y.

Application October 20, 1945, Serial No. 623,463

2 Claims. (Cl. 246—452)

1

This invention relates to railway track equipment, and more particularly pertains to the connection to a switch rod of the points of a track switch, derail switch, or the like.

It is desirable in connecting throw rods, lock rods and the like to the movable points of a track switch, to provide these connections in such a manner as not to spring the points of the track switch when such switch is operated, to hold the switch points down in their proper position, to allow for the adjustment of the switch points, and to restrict the tendency of the switch points to roll outwardly from the stock rails when the switch points are pulled up against the stock rails in the operation of the track switch.

An object of the present invention is to provide track switch rods and connectors having all of the above mentioned desirable features, such rods being particularly adapted to provide a positive supporting means against the rolling of the switch points away from the stock rails upon closure of the switch points.

Another object of the present invention is to provide for maximum adjustment in a switch point connecting rod with a minimum number of parts required, such adjustment is particularly provided so that the connection of either switch point can be adjusted without disturbing the adjustment of the other point, and without disturbing the adjustment of the throw rod or lock rod connection. The use of corresponding parts associated with lock rod and throw rod switch point connections provides maximum interchangeability of parts, and requires a minimum stock of parts for replacement.

Other objects, purposes and characteristic features of the present invention will be in part obvious from the accompanying drawings, and in part pointed out as the description of the invention progresses.

In describing the invention in detail reference will be made to the accompanying drawing in which corresponding reference characters designate corresponding parts in the different views, and in which:

Fig. 1 is a plan view of the end of a track switch showing the connection of its switch points by the front rod and throw rod connection bars as provided by the present invention;

Fig. 2 is an elevational transverse sectional view taken at the end of a track switch; and

Fig. 3 is a perspective view of the parts of a bearing or hinge assembly with its parts shown in unassembled relationship as a diagrammatic illustration of the detailed construction and manner of assembly of such parts.

2

With reference to Fig. 1, the stocks rails 2 and 3 are connected to railroad ties such as the tie 4 in the conventional manner. The track switch is shown as having a normally closed movable switch point 5 and normally open movable switch point 6. Such switch points are properly assembled into the switch track layout in the usual manner.

At the end of the switch point 5, a lug 7 is secured to the switch point for operating the detector bar 8, such lug being connected to the detector bar 8 by a suitable swivel joint 15 at its end with a resilient means to adjust for wear provided by the spring 9.

The switch points are provided with lugs for the connection of the respective rods connecting the ends of the movable points of the track switch, the lugs 10 and 11 being similar to the lugs 12 and 13 except for their being of left-hand and right-hand characters. The lug 12, for example, 20 is of rectangular bar stock and is firmly secured longitudinally to the switch point 6 by the bolts 14. The lug 12 extends beyond the end of the switch point 6, and it has a journal pin 16 formed as by forging as an integral part thereof. The 25 journal pin 16 is offset from the longitudinal portion of the lug 12, and it extends downwardly from the switch point transverse with respect to the longitudinal portion of the lug 12. The pin 16 is substantially entirely below the base of the switch point to which it is assembled, and because of its length and disposition substantially below the track rails, a rigid support against the rolling of the associated switch point is provided when the switch point is pulled up against the ball of the associated stock rail in the operation 30 of the track switch.

Each of the rods for connecting the switch points comprises two identical bar members 17, such bar members for each of such connecting rods being secured end to end and in axial alignment by a yoke 18. The yoke 18 is provided with parts for insulating the two bar members in accordance with the usual practice. In conditions where insulation is not required, the front rod can be provided as a single bar with serrations at each end.

Connected to the yoke is a suitable adjustable connector 19 in the case of the front rod for connection to the lock rod 20, and a suitable basket, or throw bar connector 21, as in the case of the 45 throw bar connection to the throw rod 22. The throw bar connection 21 can be provided, for example, as shown in my prior Patent No. 1,507,-491, dated September 2, 1924.

Each of the bar members 17 has a serrated portion 23 near the end of the bar, such serrations

extending transversely across the side of the bar for providing an adjustable mounting for the hinge or bearing used for firmly securing the switch point connecting lug to the switch point connecting bar.

With reference to Fig. 3, a split bearing is shown having a hinge member 24 and a bearing cap 25. The hinge member 24 has a serrated mounting surface 26 with the serrations extending longitudinally with the hinge member 24 for providing a rigid mounting of the bearing to the bar 17 in a manner which is readily adjustable longitudinally with such bar. The bearing comprises two cylindrical bearing surfaces spaced longitudinally and in axial alignment. Such bearing is formed by the bearing halves 27 and 28 of hinge 24 in combination with the bearing halves 29 and 30 of cap 25 respectively when the hinge 24 and the cap 25 are assembled. By the use of these two longitudinally spaced bearing surfaces, the lug 12, for example, is journaled in a manner to provide a rigid support against lateral torsional movement of switch point 6 with which it is associated, and yet provide a hinged connection to the rod 11 to allow horizontal movement of the switch point when the track switch is operated from one position to the other. Longitudinal movement of the journal 16 at the end of lug 12 within the hinge 24 and the cap 25 is restricted by shoulders 31 and 32 at the ends of the journal 16.

The bar 17 has elongated holes 34 for the mounting bolts 32 which are used for firmly securing the bearing parts 24 and 25 around the journal 16 at the end of the connecting lug 12. Such bolts also serve as a means for connecting the hinge member 24 to the bar member 17. It is believed readily apparent that the elongated holes 34 allow the shifting of the hinge member 24 along the serrations of the bar 17 longitudinally with respect to such bar to provide for proper adjustment of the connection of the switch point 6 to that bar.

After having considered specifically the structure and assembly of parts in this embodiment of the present invention, some consideration will now be given as to some of the reasons for this particular type of structure.

The use of the serrated surface manner of securing the hinge 24 to the bar 17 has several distinct advantages. First it helps to reduce lost motion between the switch point 6 and the lock rod 8 by providing a rigid hinge mounting that cannot rock or slip one way or another without requiring any dimensions of the hinge to be kept within close tolerances except for the fitting of the bearings. This also applies to the mounting bolts 32 as such bolts can have plenty of freedom within the elongated holes 34 to allow them to be easily shifted longitudinally when adjustment of the switch point is required, all without introducing lost motion into the connection of the hinge 24 to the bar member 17. It will also be noted that no close tolerances are required by the bar member 17 for any of its dimensions, including the location of the elongated holes 34.

Another advantage of the serrated manner of mounting the hinge 24 is that it reduces the number of parts required. This is true because adjustment in the connecting bars is always required, and unless such adjustment can be provided in the mounting of the hinge to the bar, additional parts for adjustment are required.

In considering again the manner in which the switch point 6 is supported against rolling when

the switch point 6, for example, is pulled up against the stock rail 3, it will be noted that securing the journal or hinge pin 16 as a part of the lug 12, which is securely bolted to the switch point, provides that the only lost motion possible is that of the fitting of the pin 16 within the hinge 24 and the cap 25. This is compared, for example, to using a system in which an eye would be formed on the end of the lug, and a free hinge pin dropped through the eye and the hinge. Under such conditions the lost motion in the eye would have to be considered in addition to any lost motion between the pin and the hinge.

From the standpoint of adjustment, the manner provided in which each switch point can be adjusted independent of the other is an ideal type of adjustment because it does not disturb the adjustment of the lock rod or throw rod connector. More specifically either switch point 5 or 6 can be adjusted, for example, without disturbing the adjustment of the connector 19, or in the case of the throw bar, without disturbing the adjustment of the connector 21.

With respect to interchangeability of parts, it will be noted that the same type of bar 17 is used on the left-hand and right-hand sides of both rods for connecting the track rails and that such bars are all interchangeable. The hinges and caps are the same type for all connecting points, and the lugs 10 and 11 are the same type and differ from the lugs 12 and 13 only in that they have a bend at their ends in an opposite direction.

The front rod arrangement provided by the present invention is particularly designed for long life with a minimum amount of maintenance required. This is particularly true in that there is only one place where movement of the track switch can cause wear, and that is in the bearings of the hinges. As a means for reducing wear at these points, a suitable lubrication fitting 36 is provided on each of the hinge caps 25, by which the lubrication chamber 35 between the bearings is filled with lubricant which is effective to lubricate both of the bearings 27 and 28 in each of the hinges.

Having thus described a means for connecting the points of a track switch as one specific embodiment of the present invention, it is desired to be understood that this form is selected to facilitate in the disclosure of the invention rather than to limit the number of forms which the invention may assume, and it is to be further understood that various adaptations, alterations and modifications may be applied to the specific form shown to meet the requirements of practice without in any manner departing from the spirit or scope of the present invention except as limited by the appended claims.

What I claim is:

1. A connector for connecting a switch point to a switch rod comprising in combination, a lug having a substantially straight longitudinal portion adapted to be secured to the side of a switch point, said lug having an integral journal pin of substantial length offset from said longitudinal portion and extending transversely from the longitudinal axis of said lug, said journal pin having longitudinally spaced limiting flanges marking the limits of a substantial journal portion of the pin, said journal portion being sufficiently spaced transversely from the longitudinal axis of said longitudinal portion of said lug to extend substantially entirely below the base of a switch point to which the lug may be secured, a split bearing adapted to couple said journal pin to a

switch rod by journaling said pin along said journal portion between said flanges, one half of said bearing having a serrated mounting surface adapted to cooperate in adjustably securing the bearing to a correspondingly serrated surface of a switch rod, said bearing having longitudinally spaced bearing contact surfaces which adjoin the respective flanges of said journal pin, whereby the spacing of the bearing surfaces provides a structure adapted to resist maximum torsional force applied to said lug with a minimum amount of friction being set up by bearing contact surfaces, and means including bolts for detachably securing the halves of said bearing together about said journal pin, said means also being adapted to secure said serrated surface by said bolts in cooperative locking engagement with the serrated surface of a switch rod, whereby the journal pin is securely journaled within the bearing when the bearing is secured to a switch rod with which the coupling may be associated, and whereby the bearing can be readily replaced without removal of the lug from a switch point.

2. A connector for connecting a switch point to a switch rod comprising in combination, a lug having a substantially straight longitudinal portion adapted to be secured longitudinally along the side of a switch point, said lug having an integral journal pin of substantial length offset from said longitudinal portion and extending transversely from said straight longitudinal portion, said journal pin having a journal portion spaced transversely from said straight longitudinal portion sufficiently to extend substantially entirely below the base of a switch point to which the lug may be secured, a split bearing adapted to couple said journal pin to a switch rod by journaling said journal pin along said journal

portion, one half of said bearing having a serrated mounting surface adapted to cooperate in adjustably securing the bearing to a correspondingly serrated surface of a switch rod, and means including bolts for detachably securing the halves of said bearing together about said journal pin, said means also being adapted to secure said serrated surface by said bolts in cooperative locking engagement with a switch rod, whereby the journal pin is securely journaled within the bearing whenever the bearing is secured to a switch rod with which the coupling may be associated, and whereby a small amount of force exerted through said bearing can balance moments about the upper portion of any switch point to which the lug may be attached because of the journal portion of the lug being spaced substantially from the longitudinal axis of the lug.
